UNITED STATES PATENT OFFICE.

CLYDE S. PELTON, OF CLEVELAND HEIGHTS, OHIO, ASSIGNOR, BY MESNE ASSIGNMENTS, TO THE PERFECTION HEATER & MANUFACTURING COMPANY, OF CLEVELAND, OHIO, A CORPORATION OF OHIO.

EXHAUST-HEATER FITTING FOR MOTOR-PROPELLED VEHICLES.

1,365,847.

Specification of Letters Patent. Patented Jan. 18, 1921.

Application filed March 24, 1917. Serial No. 157,243.

To all whom it may concern:

Be it known that I, CLYDE S. PELTON, a citizen of the United States, residing at Cleveland Heights, in the county of Cuyahoga and State of Ohio, have invented a certain new and useful Improvement in Exhaust-Heater Fittings for Motor-Propelled Vehicles, (Case G,) of which the following is a full, clear, and exact description, reference being had to the accompanying drawings.

My invention relates to motor driven vehicles and especially to vehicles driven by internal combustion engines. More particularly my invention relates to the taking and the control of the exhaust gases from engines of this type for the purpose of heating the tonneau of the vehicle.

One object of my invention is the provision of means for taking exhaust gases simultaneously from two or more exhaust pipes leading from the propelling engine whereby both or all of the pipes may be caused to supply a heater located in the vehicle body. The exhaust pipes may lead from a single engine unit or from the engines of a twin set. In the application to a vehicle driven by a twin engine unit, my invention has an additional and particular advantage in that the heating gases are taken from each engine of the twin engine unit in such a manner that the back pressures remain substantially the same on the two engines and a perfect balance is maintained between them. In carrying out my invention the two or more exhaust pipes are caused to lead into a common member and the exhaust gases for heating purposes are deflected from the common exhaust member past the muffler to the radiator, the exhaust pipes between the engine and the member being symmetrically arranged with reference thereto to insure equal resistances in the exhaust circuits. More particularly still the exhaust pipes are parallel arranged and disposed in close proximity to each other, and the common exhaust member has passages registering at one end with the exhaust pipes and converging together at the other end into a single passage, the exhaust gases for heating purposes being taken from the single passage.

For a better understanding of the above enumerated advantages of my invention

and of others which will appear hereinafter, reference may be had to the drawings accompanying this specification, Figure 1 of which is a side view, with certain parts broken away, of a muffler with connections to engine and attachments to the vehicle floor; Fig. 2 is an enlarged sectional view of the devices illustrated in Fig. 1; Fig. 3 is an enlarged plan view thereof.

The drawings illustrate a muffler and attachments for use with either a single engine unit or a twin engine, the propelling engine unit not being illustrated. The two exhaust pipes from the engine are parallel arranged and lead to inlets 1 of the exhaust receiving member 2 which member serves also as the head of the muffler 3. As set forth more particularly in my application filed on even date herewith, the head 2 is provided with an opening 4 on the top thereof and around this opening is provided a seat which is adapted to either receive a closing plate 4^a as shown in Fig. 3 or a branch fitting 5 as shown in Figs. 1 and 2 for the taking of exhaust gases from the head for heating purposes. The exhaust intake inlets 1 converge in the head 2 to a central passage and these intakes are symmetrically arranged with regard to this head 2 or its central passage whereby the exhaust gases from the two exhaust circuits encounter equal resistances in their passage to the central passage of the head 2. Since the exhaust gases encounter substantially equal resistances in the exhaust circuits the back pressures in the pipes remain substantially unchanged relatively to each other and when the propelling engine is a twin unit the balance between the two engines is therefore unimpaired. The attachment 5 is preferably a special fitting devised by me and covered in the above noted application which is adapted to be substituted for the plate covering the opening when the heating system is to be installed. This attachment comprises a disk valve 6 mounted for rocking movement on an axis passing through the plane of the disk, and this disk is adapted to project down into the central passage of the head 2 toward the engine unit and thereby deflect a portion of the exhaust gases out through the branch fitting 5 to a radiator located in the tonneau of the vehicle. The branch fitting 5 has a flexible pipe connection 7 lead-

ing to the radiator connection on the floor body illustrated in Fig. 1.

The muffler shown in these drawings comprises an outer cylindrical casing, a central 5 smaller tube 8 located therein and communicating with the central passage in the head 2, and an intermediate tube 9 located between the two. The tubes 8 and 9 are formed with perforations at opposite ends 10 thereof for the escape of the gases, which finally reach the atmosphere through a pipe 10 interposed between one side of the tube 9 and the outer casing. I have here shown a second flexible tube 11 controlled by a 15 valve 12 leading from the tube 8 to a second heater 13 also located above the car floor. Both heaters are illustrated as provided with discharge fittings 15.

While I have set forth my invention in 20 the specific manner required by the patent statutes it is understood that the claims hereto attached are intended to cover the various forms my invention is capable of assuming, and are not to be limited in scope 25 except as is required by the prior art.

Having thus described my invention, what I claim is:

1. In a vehicle propelled by an internal combustion engine, the combination with 30 two exhaust pipes leading from said engine, of a fitting having a single passageway with which both pipes communicate, the wall of said passageway being formed with an opening 35 symmetrically arranged with reference to said pipes and adapted to receive a branch connection leading to a heater.

2. In a vehicle propelled by an internal combustion engine, the combination with 40 two exhaust pipes, of a fitting having a single passageway with which both pipes communicate, the wall of said passageway being formed with an opening symmetrically arranged with reference to said pipes, a branch fitting connected to said first fitting 45 and communicating with said opening, and a valve in said branch fitting having a part adapted and arranged to obstruct the passage through said first fitting when the valve is opened and so deflect gases into said 50 branch.

3. An exhaust fitting for engine propelled vehicles comprising a member having a single passageway for communicating with a

muffler and a pair of diverging passageways terminating in sockets for the reception of twin exhaust pipes, said passageways being symmetrically arranged with reference to said members whereby the back pressure in said exhaust pipes are maintained substantially the same, said member 60 having an opening in its side, and a branch fitting adapted to be secured to said opening comprising a valve for deflecting a portion of the gases from said member.

4. In a vehicle propelled by an internal 65 combustion engine, the combination with two exhaust pipes, of a common member to which said pipes are connected, said member having an opening in its side symmetrically arranged with reference to said pipes 70 whereby back pressures on said engine are maintained substantially the same, and a branch fitting adapted to be secured to said opening comprising a valve for deflecting a part of the gases from said member for the 75 purpose described.

5. An exhaust fitting for engine propelled vehicles, comprising a member having a single passageway for communication with a muffler and a pair of diverging passageways 80 terminating in sockets for the reception of twin exhaust pipes, said member having a lateral opening communicating with said single passageway and surrounded by a flat flange whose plane is parallel to the plane 85 which includes the axes of both pipes and whose face forms a seat adapted to receive a plate whereby the opening may be closed or a branch fitting communicating with the 90 opening.

6. An exhaust fitting for engine propelled vehicle comprising a member having a pair of converging passageways merging with a single passageway, said member having means whereby twin exhaust pipes can be secured thereto in communication with said converging passageways, respectively, and other means whereby said single passageway can be placed in communication with the interior of a muffler, and the wall of said single passageway being formed with an opening symmetrically arranged with respect to said converging passageways.

In testimony whereof, I hereunto affix my signature.

CLYDE S. PELTON.
